PAINT CAN SHAKER

Frank W. Krueger, San Carlos, Calif., assignor to Ralston Manufacturing Company, Belmont, Calif., a corporation of California

Application October 3, 1956, Serial No. 43,211

Term of patent 3½ years

(Cl. D55—1)

Fig. 1

Fig. 2

Fig. 3

Fig. 4

Fig. 5

Fig. 1 is a front elevation of a paint can shaker showing my new design;

Figs. 2 and 3 are side and rear elevational views, respectively, thereof;

Fig. 4 is a top plan view of a paint can shaker with the can clamps omitted for convenience of illustration; and

Fig. 5 is an enlarged perspective view thereof as shown in Fig. 4.

The essential features of the design reside in the portions shown in full lines.

I claim:

The ornamental design for a paint can shaker, as shown and described.
